UNITED STATES PATENT OFFICE.

LUCIUS A. LE MIEUX, OF SEYMOUR, WISCONSIN.

STEAM-ENGINE VALVE.

SPECIFICATION forming part of Letters Patent No. 465,670, dated December 22, 1891.

Application filed April 3, 1891. Serial No. 387,548. (No model.)

To all whom it may concern:

Be it known that I, LUCIUS A. LE MIEUX, a citizen of the United States, and a resident of Seymour, in the county of Outagamie, and in the State of Wisconsin, have invented certain new and useful Improvements in Steam-Engine Valves; and I do hereby declare that the following is a full, clear, and exact description thereof.

10 My invention relates to certain new and useful improvements in steam-engine valves, and relates more particularly to a novel construction in rotary valves of the same general construction as that shown in a prior patent, granted to me on November 25, 1890, and numbered 441,176.

The invention consists in the matters hereinafter described, and pointed out in the appended claims.

20 In the accompanying drawings, illustrating my invention, Figure 1 is a longitudinal section of a rotary valve embodying my invention. Fig. 2 is a cross-section of the same on line 2 2 of Fig. 1. Fig. 3 is a cross-section on line 3 3 of Fig. 1. Fig. 4 is a longitudinal sectional view illustrating a modified form of my improvement, taken on line 4 4 of Fig. 5. Fig. 5 is a cross-section on line 5 5 of Fig. 4. Fig. 6 is a separate view of one of the parts.

30 In said drawings, A indicates a cylindrical steam-chest, provided with steam inlet and exhaust ports a and a' , respectively, and with ports a^2 a^2 , leading to the opposite ends of the cylinder.

35 B indicates as a whole the rotary valve, which comprises a frame provided with cylindrical ends B' B' , connected together by parallel bars or side walls b b , said frame being centrally supported within the cylindrical steam-chest upon a shaft B^3 , by means of which motion is communicated to the valve through the medium of any suitable mechanism. Packing-rings B^2 B^2 are located upon the outside of the two end portions B' B' of the valve-frame, as shown in Figs. 1 and 2 of the drawings.

40 C C are valve-plates of substantially T shape, said valve-plates being adjustably engaged with the valve-frame B.

45 As shown in the drawings, the shank of each of the T-shaped valve-plates C C is movably engaged between the two parallel side

walls b b of the said frame, and the outer portions of said valve-plates are curved, so as to fit closely against the inner surface of the steam-chest A.

In order to keep the valve-plates C C constantly pressed outwardly against the inner surface of the steam-chest, I provide means for introducing steam into the interior of the valve, between the inner ends of the valve-plates C C. As shown in Figs. 1, 2, and 3, I provide a duct D upon the inner surface of the steam-chest A, said duct communicating with a peripheral groove D' upon the outer surface of one of the packing-rings B^2 B^2 , and a radial duct D^2 , leading to the center of one of the cylindrical ends B' B' of the valve-frame and communicating with the peripheral groove or duct D' at its outer end. The duct or groove D is located in the inner surface of the steam-chest in such a position as to open into the steam-inlet port, so as to afford a constant supply of steam to the interior of the valve. By this construction steam is permitted to enter through the ducts D, D', and D² to the interior of the valve, and the steam thus admitted serves to press the two valve-plates outwardly against the walls of the steam-chest, so as to prevent any leakage of steam between the said valve-plates and the walls of the steam-chest.

In the form of construction shown in Figs. 4, 5, and 6 a steam-passage E is provided in each of the valve-plates, said passages being arranged to come alternately into communication with the steam-inlet port as the rotary valve is revolved by the valve-actuating mechanism. A reciprocating valve E' is located between the plates C C and is provided with two bearing-surfaces, preferably of substantially conical form, arranged to engage correspondingly-shaped seats e e in the two valve-plates C C. Two stems e' e' are provided upon the opposite ends of the reciprocating valve E', said stems being arranged to move loosely within the steam-passages E, as shown in Figs. 4 and 5. By this arrangement a sufficient space is left outside of the stems e' e' to permit steam to enter through the inside of the passages E E and around the stems e' e' to the inside of the rotary valve, so as to press the two valve-plates outwardly against the walls of the steam-chest. The stems e' e' are

made of tubular form, so as to admit steam to the inside of the valve E' also, and said valve is provided with a diaphragm E² upon its inside to prevent the steam from passing through the said valve E'. By this arrangement, when the passage E in one of the valve-plates C comes into communication with the steam-inlet port, steam immediately enters through said passage to the interior of the valve E' and by its pressure upon the diaphragm E² forces said valve against the seat in the opposite valve-plate C. At the same time steam passes around the outside of the stem e' and enters the space between the two valve-plates C C, thereby operating to hold said valve-plates closely against the walls of the steam-chest and to prevent any leakage of steam past said plates. In this form of construction, also, the outer surfaces of the valve-plates C C are provided with short transverse grooves e² e², communicating with the outer ends of the steam-passages E E and extending nearly to the edges of the bearing-surfaces of the said valve-plates, so that as soon as one of said valve-plates begins to move across the steam-inlet port the steam will pass through said transverse groove and immediately enter the passage E, so as to hold the valve-plates outwardly against the walls of the steam-chest, as before described.

By my improvements I am enabled to provide a rotary valve which works with the least possible amount of friction, being practically balanced by the steam-pressure, and also working smoothly and tightly with varying degrees of steam-pressure.

A great advantage of the constructions herein described over the form shown in the before-mentioned prior patent, in which the valve-plates are held apart by springs, is that in order to insure the operation of the rotary valve under varying degrees of steam-pressure the springs which hold said valve-plates apart must be made sufficiently strong and stiff to hold said valve-plates outwardly against a heavy steam-pressure, so that when steam under a lesser pressure is used the friction caused by the outward pressure of said springs is greater than if the springs were only stiff enough to hold the valve-plates outward against the steam under this lesser pressure, while by the forms of construction herein described the pressure of the steam between the valve-plates to hold said plates apart is always proportionate to the pressure

of the steam in the inlet-port. This arrangement therefore produces a much more satisfactory operation of the valve under varying degrees of pressure. By my improvements, also, I am enabled to provide a rotary valve of very simple construction and one in which the parts may be readily removed for inspection or repair.

Having described my invention, what I claim is—

1. The herein-described rotary valve for steam-engines, comprising a revoluble frame carrying two valve-plates expansibly connected therewith, and means for introducing live steam between the said valve-plates upon the interior of said frame, substantially as and for the purpose described.

2. The herein-described valve for steam-engines, comprising a revoluble frame having cylindrical end portions and parallel longitudinal side bars or walls, two valve-plates expansibly connected with said side bars or walls, and means for introducing live steam between said valve-plates upon the interior of said frame, substantially as described.

3. The herein-described rotary valve for steam-engines, comprising a revoluble valve-frame provided with cylindrical end portions and parallel longitudinal side bars or walls, two valve-plates expansibly engaged with said longitudinal walls, and a steam-passage communicating at one end with the steam-inlet port and at the other end with the space between the inner ends of said valve-plates within said revoluble frame, substantially as described.

4. The herein-described rotary valve for steam-engines, comprising a rotary frame having cylindrical end portions and parallel longitudinal side bars or walls, two valve-plates of substantially T shape expansibly engaged with said side walls, and a steam-passage leading from the steam-inlet port and communicating with the space between the inner ends of said valve-plates within said revoluble frame, substantially as and for the purposes described.

In testimony that I claim the foregoing I have hereunto set my hand, at Milwaukee, in the county of Milwaukee and State of Wisconsin, in the presence of two witnesses.

LUCIUS A. LE MIEUX.
